C. T. DRAPER.

CLOSURE MEMBER FOR SHEET METAL CONTAINERS.

APPLICATION FILED APR. 9, 1917.

1,436,021.

Patented Nov. 21, 1922.

Inventor:

Charles T. Draper,

B. A. Warner
Attorney.

UNITED STATES PATENT OFFICE.

CHARLES T. DRAPER, OF CLEVELAND, OHIO, ASSIGNEE TO THE DRAPER MANUFACTURING COMPANY, OF CLEVELAND, OHIO, A CORPORATION OF OHIO.

CLOSURE MEMBER FOR SHEET-METAL CONTAINERS.

Application filed April 9, 1917. Serial No. 160,660.

To all whom it may concern:

Be it known that CHARLES T. DRAPER, a citizen of the United States, residing at Cleveland, in the county of Cuyahoga, and State of Ohio, has invented certain new and useful Improvements in Closure Members for Sheet-Metal Containers, of which the following is a specification.

My invention relates to improvements in closure members for sheet metal containers, and has for its object the provision of means for sealing such containers, which means are highly efficient and cheaply constructed. The most common use for which my improvement is designed, is that of sealing sheet metal barrels or containers, but I have shown as one of the adaptations of my improvement, a sheet radiator equipped in accordance with my invention.

Referring to its use in connection with sheet metal barrels, this improvement secures a thoroughly efficient closure by reason of the fact that the seal is effected by screw pressure upon the body portion of the barrel. In other words, the body portion is clamped, preferably with a gasket intervening, between screw-acting members positioned respectively exteriorly and interiorly of the barrel, and there are no seams, joints or welds between the barrel body and its closure members, which otherwise would require liquid tight construction. Moreover, one of the screw-acting members, which is interiorly positioned within the receptacle and therefore unsubjected to damage or displacement, is securely interlocked with the sheet metal body itself in order to afford ample resistance to the torsion or strain of forcibly tightening the screw threads and effecting the exterior seal.

I may briefly describe the preferred construction in its simplest form, as comprising the perforated body portion of the sheet metal container, with which an interiorly positioned tapped crown or metallic ring, registering with said perforation, is securely interlocked to hold the members in fixed relation. The seal or closure is effected by an exterior, flanged screw-plug which takes within the tapped crown and clamps a gasket between its flange and the barrel body in sealing relation. The features of my improvement may be more readily explained in

detail, by making reference to the accompanying drawings, wherein:—

Fig. 1, is a view in perspective, showing a sheet metal barrel or container equipped with my improvement.

Fig. 2 is an enlarged sectional view of the closure members of the sheet metal container.

Figs. 3 and 4 are similar sectional views of the body portion and the tapped crown thereof, respectively, and

Fig. 5 is a detail partially broken away and in section, illustrating radiator-sections thus equipped and connected together.

Throughout the several figures of the drawing, I have employed the same character of reference to indicate similar or equivalent parts.

Although I have shown containers, as I may term the sheet metal barrel and radiator, equipped with my improvements of identical characteristics, the structural features of my invention are not necessarily confined to the details shown, nor to the uses indicated for the purpose of explanation.

In Fig. 1 I have shown a sheet metal barrel *a*, the metallic head *b* having two openings closed by screw caps or plugs *c* *d*. Either or both of these may be constructed in accordance with my present invention, but the former is intended or contemplated by the further description and drawing. Thus in Figs. 2, 3 and 4 the barrel body portion or head *b* is slightly elevated at *b'* about the perforation or opening *d* and the edges or lips *b''* initially are downturned as shown in Fig. 3.

Fig. 4 illustrates in section, the tapped crown or ring *e*, which conveniently may be a malleable casting having integral lugs or securing members *e'* peripherally arranged about its upper edge and adapted to be firmly interlocked beneath the lips *b''* for the purpose of securing said ring firmly in position interiorly of the barrel, as shown in Fig. 2. The screw plug *f* has a flange *f'* which is adapted to bear upon the gasket *g* interposed between the elevated rim *b'* and said flange *f'*. Accordingly, it will be seen that the seal is effected directly between the screw-acting members *e* and *f*, so that there is no dependence upon any seam or weld for making the container strictly liquid tight.

This feature will be best appreciated by

those who are conversant with the art of manufacturing sheet metal containers, and particularly large containers such as are designed for holding gasoline, alcohol, turpentine and many other liquids difficult to retain, when seams or joints are involved. In ordinary barrel construction an exteriorly positioned crown for seating the screw plug, previously has involved a welded or over-lapping joint between the body portion and the crown, which of necessity must be liquid tight and thereby becomes expensive to manufacture. Moreover, the welding operation, not infrequently burns the sheet metal body portion, meaning its impairment through overheating by the oxy-acetylene flame.

All of this is avoided by the construction herein explained, as well as the frequent warping of the ring caused by unequal and excessive heating, during welding. In assembling my closure members, the malleable casting *e* is trued between conforming dies, preferably, before it is used in the assembling die to interlock the lugs *e'* beneath the inturned lips *b''* of the body portion or head. As thus interlocked in said assembling die the inturned rim *b''* and the sheet metal seat are forcibly compressed so that the metal is very slightly thinned above and below the overturned lugs *e'*, between which are retaining indentations, so that the ring *e* is securely held against displacement and all twisting or turning strains. When the members are thus assembled, as shown in Fig. 2, the ring maintains its initial and accurate shape and position with respect to the opening, so that the screw plug will fit accurately therein and secure an effective seal, dependent upon the pressure exerted by the screw-acting members. Thus the gasket may safely be relied upon for effecting the temporary sealing relation of the container equipped with my improvements. The body of the container preferably is slightly elevated about the opening, better to afford a broad, level annular seat for the screw-plug or gasket, directly upon the body-portion. This is obtainable for the purpose of securing a most effective seal, through positioning the supporting ring beneath the opening and wholly within the container. Fig. 5 illustrates details of two sheet metal radiator sections *h*, *h*, fitted with my improved closure members, as an illustration or example of the further adaptation of this invention. The members are of identical type; the only difference of note being the substitution of a threaded pipe-section *i* for the screw plug of the other figures, but the principles and advantages of my improvements are retained. Other adaptations will readily occur to one skilled in the art, and need not be specifically mentioned.

Having now described the preferred em-

bodiment of my invention, and two distinct modes of practically applying it in use, I claim and desire to secure by Letters Patent, together with such modifications as may be made by mere skill, the following:—

1. A closure for sheet-metal containers, comprising a circularly perforated wall of said container having an inwardly turned rim, a metallic ring positioned wholly interior of the container having integral members interlocked with said rim and a tapped portion substantially registering with said inwardly turned rim; said perforated wall being formed to provide an annular seat, and a closure member having an enlarged head adapted to be screwed into the tapped portion of the ring and effect an exterior seal with said annular seat, substantially as set forth.

2. A closure for sheet-metal containers, comprising a circularly perforated wall of said container having its rim turned inwardly, a metallic ring provided with rigid indented engaging members interlocked with said rim and with a tapped portion; all substantially registering with said perforation but positioned wholly interior of the container, and a closure member having an enlarged head annularly extending above the interiorly positioned ring and screwing into its tapped portion to effect an exterior seal with said container wall, substantially as set forth.

3. A closure for sheet-metal containers, comprising the perforated sheet-metal body portion, an annular securing crown positioned wholly within the interior of the container and registering substantially with said perforation; said crown having bendable portions rigidly interlocked with the perforated sheet-metal and fixedly securing it in position, and a flanged closure plug clamping the body portion in sealing relation between its flange and the interior crown, substantially as set forth.

4. A closure for sheet-metal containers, comprising a circularly perforated wall of said container having a reverting rim, a ring positioned wholly interior of the container and rigidly interlocked to said reverting rim substantially in register with the perforated opening; the exterior of the opening being flattened to form a closure seat, a gasket positioned upon the seat, a flanged closure member adapted to bear upon the gasket in sealing relation immediately above the annular edge of the opening, and means for effecting its clamping engagement to effect an exterior seal, substantially as set forth.

5. The combination with the body portion of a sheet-metal container suitably perforated with an ingress opening, of a tapped malleable ring having peripheral spaced securing members integral therewith; the rim of said opening and the securing mem-

- bers being interlocked with the ring wholly 5 interior of the container, a gasket bearing exteriorly of the opening, and a screw-plug taking within the ring and seating the gasket upon the body portion in exterior sealing relation, substantially as set forth.
6. The combination with a sheet metal body portion having a round opening therein, of a malleable annular member having 10 peripheral securing parts and a tapped portion approximately the diameter of the completed opening; the said peripheral securing parts and the rim of said opening being interlocked substantially in a horizontal plane above the tapped portion for securing the tapped annular member in place, and a flanged screw plug adapted to be inserted in the tapped annular member and clamp the body portion between it and its 15 flange, substantially as set forth.
7. The combination with a sheet metal body portion of a container having a circular opening therein, of a malleable annular member having peripheral members interlocked with the sheet-metal and a tapped portion slightly less in diameter than the finished opening; the body of the metal being slightly elevated to form a seat, and its rim about the opening and the securing 20 25
- parts being interlocked interiorly of the container approximately in the plane of the unelevated sheet metal body portion, and a flanged screw plug adapted to be inserted in the tapped annular member with its flange bearing upon the elevated annular seat 30 35 formed from the body portion, substantially as set forth.
8. A sheet metal container having an opening for filling and emptying its contents formed in the body thereof, an interiorly positioned tapped annular member secured beneath said opening entirely within said container; its tapped portion being approximately the diameter of the completed opening in the body and its upper portion being securely interlocked with the rim of said opening, and a flanged screw plug adapted to be inserted in the tapped portion with its flange in sealing exterior engagement with the body portion of the container, substantially as set forth.

In testimony whereof I do now affix my signature in the presence of two witnesses.
